UNITED STATES PATENT OFFICE.

JOHN J. PUNKE, OF DETROIT, MICHIGAN, ASSIGNOR TO HUPP MOTOR CAR CORPORATION, OF DETROIT, MICHIGAN, A CORPORATION OF MICHIGAN.

DESIGN FOR A DOOR-WINDOW REGULATOR HANDLE.

Application filed May 28, 1928. Serial No. 26,893. Term of patent 7 years.

To all whom it may concern:

Be it known that I, JOHN J. PUNKE, a citizen of the United States of America, residing at Detroit, in the county of Wayne, and State of Michigan, have invented a certain new, original, and ornamental Design for a Door-Window Regulator Handle, of which the following is a specification, reference being had therein to the accompanying drawing in which—

Figure 1 is a top plan view of my handle.

Fig. 2 is a side elevation of my handle. Fig. 3 is a bottom plan view of the handle shank and Figures 4, 5, 6 and 7, respectively, are enlarged sectional views taken on the lines 4—4, 5—5, 6—6, and 7—7, respectively of Figures 1 and 2.

I claim:

The ornamental design for a door window regulator handle, substantially as shown.

JOHN J. PUNKE.
